US00D504715S

(12) **United States Design Patent** (10) Patent No.: **US D504,715 S**
(45) Date of Patent: **** May 3, 2005**

(54) **VALVE**

(75) Inventor: **Syunichiro Hagihara, Nobeoka (JP)**

(73) Assignee: **Asaki Organic Chemicals Industry Co., Ltd., Nobeoka (JP)**

(**) Term: **14 Years**

(21) Appl. No.: **29/200,192**

(22) Filed: **Feb. 26, 2004**

(30) **Foreign Application Priority Data**

Sep. 1, 2003 (JP) 2003-025459

(51) LOC (7) Cl. **23-01**

(52) U.S. Cl. **D23/235; D23/245**

(57) **CLAIM**

The ornamental design for a valve, as shown and described.

DESCRIPTION

FIG. 1 is a rear perspective view of a valve showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof;

FIG. 8 is a cross-sectional view taken along the line 8—8 in FIG. 6;

FIG. 9 is a cross-sectional view taken along the line 9—9 in FIG. 6;

FIG. 10 is a rear perspective view of the valve when the upper main body rotates 90 degree;

FIG. 11 is a rear perspective view of the valve when the upper main body rotates 180 degree; and,

FIG. 12 is a rear perspective view of the valve when the upper main body rotates 270 degree.
